UNITED STATES PATENT OFFICE.

EARL R. GREELEY, OF SYRACUSE, NEW YORK, ASSIGNOR TO PIERCE, BUTLER & PIERCE MANUFACTURING CORPORATION, OF SYRACUSE, NEW YORK, A CORPORATION OF NEW YORK.

HEATER.

1,308,669.

Specification of Letters Patent.

Patented July 1, 1919.

Application filed February 7, 1916. Serial No. 76,646.

To all whom it may concern:

Be it known that I, EARL R. GREELEY, a citizen of the United States, and a resident of Syracuse, in the county of Onondaga 5 and State of New York, have invented a certain new and useful Heater, of which the following is a specification.

This invention relates to heaters as boilers for heating buildings and has for its object a particularly simple and efficient means for adjusting the boilers for burning different kinds of fuel, and for also adjusting the amount of fuel to be consumed in the boilers; and the invention consists in the novel 15 combination and construction hereinafter set forth and claimed.

In describing this invention reference is had to the accompanying drawings in which like characters designate corresponding 20 parts in all the views.

Figure 1 is a front elevation of a sectional boiler embodying my invention.

Fig. 2 is a vertical sectional view thereof.

This heater comprises generally a boiler 25 having a vertical fuel passage, a wall of the passage being adjustable to vary the size and shape of the passage. This wall is usually adjustable rectilinearly or about axes located at its upper and lower ends.

30 I have here illustrated my invention as embodied in that type of heaters known as sectional boilers which are composed of end sections 1, and intermediate sections 2, which may be of any suitable form, size and construction.

35 The end sections are usually formed with portions or projections 3 extending in front of the front edges of the intermediate sections, and the front wall is located between the projections 3 and opposed to the front ends of the intermediate 40 sections, forming a vertical fuel passage 4 at the lower end of which the grate 5 is located. A hopper 6 is located at the upper end of said passage.

45 7 is a wall opposed to the front walls of the intermediate sections and located between the extensions 3 of the end sections and forming the front side of the passage 4, this wall being adjustable forwardly and

50 rearwardly to regulate the size of the passage 4. This wall is preferably formed hollow and is what is usually known as a water front and the interior thereof is connected to the interior of the end sections by pipes

55 8, 9 connected to the upper and lower ends

thereof, these pipes including sections 10, 11 about which either end of the water front may swing about as axes and also including sections which are joined by sleeve nuts 12 by means of which the pipes can be adjusted in lengthwise directions. By manipulation of the sleeve nuts, the water front may be adjusted rectilinearly, forwardly and rearwardly or either end thereof may be adjusted about the pivot at the other 65 end, the movement of the water front being permitted by the slots 13 in the extensions 3 through which slots the pipes extend.

The water front is also provided with a down draft passage 14 having laterally extending and downwardly inclined branches 14^a opening into the passage 14.

The adjustable water front is connected to the hopper by adjustable connections consisting of wall sections 16, 17 pivoted respectively at 18 and 19 to the hopper 5 and the water front 7, these wall sectionslapping each other and being connected by a pin-and-slot connection 20.

During the adjustment of the water front 80 7, thelapping portions of the wall sections 16, 17 will slide relatively to each other.

By manipulating the sleeve nuts 12 and swinging the water front 7 about either of its axes 10, 11 or by moving the water front 85 rectilinearly inwardly or outwardly the size and shape of the passage 4 can be adjusted to suit the kind or quantity of coal to be used. The slots 13 are closed by the usual asbestos or other plastic covering of the boiler. 90

What I claim is:

1. A boiler having a vertical fuel passage, a water wall connected to the boiler and forming one of the walls of the fuel passage and forming a fuel magazine, the 95 water wall being pivoted and adjustable on its pivot, and water pipe connections connected to the water wall at a point remote from its pivot, said pipe connections being adjustable to conform to the pivotal 100 adjustment of the water wall, substantially as and for the purpose described.

2. A heater having a vertical fuel passage and a wall forming one side of the passage, said wall being pivoted at its upper and 105 lower ends and adjustable rectilinearly forwardly and rearwardly or adjustable about either one of its pivoted ends, substantially as and for the purpose specified.

3. A boiler having a vertical fuel pas- 110

sage, a hollow water wall connected to the boiler and forming one of the walls of the fuel passage, and pipes connecting the opposite ends of said hollow wall and the boiler, 5 the wall being adjustable forwardly and rearwardly, and said pipes being pivotally connected to opposite ends of said wall and being adjustable in a lengthwise direction, substantially as and for the purpose set forth.

4. A boiler having a fuel hopper, a vertically extending fuel passage leading from the hopper, the outer wall of the passage being adjustable inwardly and outwardly toward and from the body of the boiler to narrow or widen said fuel passage, a wall connecting the former wall and the hopper to permit the adjusting movement of the former wall, said connecting wall including sections hinged respectively to the hopper and to the former wall, the sections lapping each other during the adjustment of

the former wall, and means for holding the lapping portions from separation, substantially as and for the purpose specified. 25

5. A sectional boiler comprising end sections which project in front of the intermediate sections, a hollow water front interposed between the front ends of the end sections and forming a vertical fuel passage, 30 a hopper above the fuel passage and adjustably connected to the water front, said water front being adjustable forwardly and rearwardly, and pipes connecting the end sections and the water front, the pipes being pivotally connected to the upper and lower ends of the water front and being adjustable in lengthwise directions, substantially as and for the purpose set forth.

In testimony whereof, I have hereunto signed my name, at Syracuse, in the county of Onondaga, and State of New York, this 17th day of January, 1916.

EARL R. GREELEY.

Copies of this patent may be obtained for five cents each, by addressing the "Commissioner of Patents, Washington, D. C."
